CLAIM

The ornamental design for a shoe as shown and described.

DESCRIPTION

FIG. 1 is a rear perspective view of a shoe showing our new design; and,

FIG. 2 is an enlarged view encompassing the claimed region of FIG. 1 with environment outside the disclaimed boundary removed for clarity purposes.

The broken line immediately adjacent to and surrounding the photographic area defines the peripheral bounds of the claimed design and forms no part thereof. The broken lines within the photographic area represent eyelets that form no part of the claimed design. The broken lines depicting the remainder of the shoe form no part of the claimed design.
